ATTORNEY.

UNITED STATES PATENT OFFICE.

FREDERICK H. WOOD, OF CLEVELAND, OHIO, ASSIGNOR OF ONE-HALF TO
A. A. WENIAM, OF SAME PLACE.

DESIGN FOR A HORSE-BOOT.

SPECIFICATION forming part of Design No. 23,920, dated December 25, 1894.

Application filed November 12, 1894. Serial No. 528,585. Term of patent 14 years.

To all whom it may concern:

Be it known that I, FREDERICK H. WOOD, a citizen of the United States, residing at Cleveland, in the county of Cuyahoga and State of Ohio, have invented and produced a new and original Design for Boots for Horses, of which the following is a specification, reference being had to the accompanying drawings, showing a part thereof.

10 Figure 1 is a perspective view of my novel design in horse boots, and Fig. 2 is a vertical edge view thereof, enlarged considerably over Fig. 1 and serving to more clearly show the shape thereof and the proportions or thicknesses of the boot at different points between its upper and lower edges.

15 The novelty of the design is in the shape or contour of the boot as a whole. This shape or contour comprises, first and mainly, the 20 substantially spherical body —2—, and, secondly, the narrow collar —4— about the top of the body. In cross section vertically at

any point, as is clearly seen at each edge —5— of the drawings, there is a slight taper in both directions from the deepest or thickest point —8— at about the center of the spherical portion —2— and then there is a more abrupt taper from the outside as each edge —9— and —10— at top and bottom respectively is reached. The outer and inner 25 surfaces of the boot are plain and smooth, and ornamental bands —12— overlap the open space between the opposite edges at top and bottom.

Having thus described my invention, what 30 I claim as new, and desire to secure by Letters Patent, is—

The design for a boot for horses substantially as herein shown and described.

FREDERICK H. WOOD.
